HINGE CONSTRUCTION

Albert J. Allen, Brooklyn, N. Y., assignor to Metropolitan Device Corporation, a corporation of New York

Application July 26, 1938, Serial No. 221,291

2 Claims. (Cl. 16—192)

The invention herein disclosed relates to a construction for pivotally securing a cover or door to a support and more particularly to a hinge construction for pivotally securing a cover on a box or a door on a cabinet.

In the prior Patent No. 2,092,582 granted September 7, 1937, there is disclosed a hinge construction that essentially comprises a heavy metal wire having end sections shaped to form substantially semicircular loops. The plane of these loops is perpendicular to the axis of the wire and extends through, for example, the side wall and cover of a box or cabinet. It is possible, where such a hinge construction is utilized on a box or cabinet that is normally locked or sealed, as for example, a box or cabinet enclosing the electrical connections to an electric meter, for an unauthorized person to open the box by bending the portion of the wire forming the hinge loop; and it is an object of the present invention to provide a hinge construction that is as simply and easily constructed as the hinge construction of the aforesaid patent, but in which construction both ends of the hinge loops are secured within the box.

In accordance with the invention there is provided, for a box or cabinet having a cover, a hinge construction that comprises two heavy metal wires. Each wire is bent back upon itself and the loop so formed is bent to extend at right angles to the axes of the wire thus forming a hinge loop. The hinge loop formed by each wire extends through the side wall of the box and the cover and pivotally secures the cover to the box. Both ends of each wire are secured to the inner surface of the box.

Such a hinge construction is illustrated in the accompanying drawing in which:

Fig. 1 is an isometric view of a fragment of a box with the cover hingedly secured thereto;

Fig. 2 is a section of the same taken on the line 2—2 of Fig. 1; and

Fig. 3 is a section of the same taken on the line 3—3 of Fig. 1.

In the drawing 1 represents the bottom of the box, 2 an end wall and 3 the side wall to which the cover 4 is hinged. The cover 4 has flanges 4a and 4b along each side edge extending perpendicular to the plane of the cover. In the closed position of the cover, these flanges overlap the side walls of the box.

The cover 4 is hinged to the side wall 3 of the box through the flange 4a which is provided with a pair of openings 4c therethrough to receive the hinges. There are two hinges 5 and 6 which are identical in all respects. The hinge 5 is made

from a piece of heavy metal wire that is bent back upon itself to form a loop 5a and two parallel legs 5b and 5c of equal length. The loop 5a is bent at right angles to the axis of the legs 5b and 5c or to the plane containing the axis of the legs, thus forming a hinge loop. This hinge loop extends through a slot 3a formed in the side wall 3 and through the pair of openings 4c in the flange 4a of the cover adjacent the slot 3a. The cover is thus pivotally secured to the side wall 3 by the hinge loop 5a.

The legs 5b and 5c of the hinge 5 extend along the inner surface of the side wall 3. The legs 6b and 6c also extend along the inner surface of the side wall 3 and towards the legs 5b and 5c. The hinge loop 6a of the hinge 6 extends through a slot 3b in the side wall 3 and through the other of the pair of openings 4c in the flange 4a of the cover.

The two pair of legs of the hinges 5 and 6 are secured to the inner surface of the side wall 3 by a plate 7. The plate 7 has a pair of retaining portions 7a at each end of the plate to receive the ends of the legs of the hinges. This plate with the ends of the legs of the hinges beneath it is secured to the inner surface of the box.

From the foregoing it will be seen that by this invention there is provided a simple hinge construction that consists of a heavy metal wire that leaves and reenters the box forming a closed loop which can not be forced open.

It will be obvious that various changes may be made by those skilled in the art in the details of the embodiment of the invention disclosed in the drawing and described above within the principle and scope of the invention as expressed in the appended claims.

I claim:

1. A loop hinge construction for a box having a slot in the side wall thereof and a cover having an opening therethrough which hinge construction consists of a single piece of heavy metal wire and which includes two leg portions joined at adjacent ends by a semi-circular loop portion, extending at right angles to the plane of the axes of the leg portions and forming a hinge loop extending through the slot in the side wall of the box and through the opening in the cover, and means for securing the ends of the leg portions to the inner surface of the side wall of the box. 50

2. A loop hinge construction for a box having a pair of spaced slots in one side wall and a cover having a pair of spaced openings therethrough arranged to align with the slots through the side wall, which hinge construction comprises two 55

heavy metal wires, each wire including two leg portions joined at adjacent ends by a semi-circular loop portion, the loop portion of one of said wires extending through one of the slots in the side wall of the box and the adjacent opening through the cover, and the loop portion of the other wire extending through the other slot in the side wall of the box and the adjacent opening

through the cover, the leg portions of both wires extending towards the center line of the side wall, and a plate having pressed out portions to receive the ends of the leg portions of the wires and secured to the inner surface of the side wall of the box. 5

ALBERT J. ALLEN.
